UNITED STATES PATENT OFFICE.

MORRIS P. HOLMES, OF CLAREMONT, NEW HAMPSHIRE, ASSIGNEE, BY MESNE ASSIGNMENTS, TO THE JEFFREY MANUFACTURING COMPANY, OF COLUMBUS, OHIO, A CORPORATION OF OHIO.

MINING MACHINE.

Original application filed November 27, 1908, Serial No. 464,723. Divided and this application filed March 12, 1910, Serial No. 548,769. Renewed February 13, 1922. Serial No. 536,369.

To all whom it may concern:

Be it known that I, MORRIS P. HOLMES, a citizen of the United States, residing at Claremont, county of Sullivan, and State of New Hampshire, have invented an Improvement in Mining Machines, of which the following description, in connection with the accompanying drawings, is a specification, like letters on the drawings representing like parts.

My invention relates to mining machines, being more particularly intended to provide improved means for feeding and guiding a mining machine while it performs the cutting operation.

This application is a division of my prior pending application Serial No. 464,723, filed November 27, 1908.

My invention will be best understood by reference to the following description when taken in connection with the accompanying illustration of one specific embodiment thereof, while its scope will be more particularly pointed out in the appended claims.

In the drawings:

Fig. 1 shows in plan partially broken away a mining machine embodying one form of my invention.

Fig. 2 is a central, sectional plan showing the speed reduction gearing for the cable winding drum on the machine in Fig. 1.

Fig. 3 is an elevation partly in section showing the mining machine of Fig. 1.

Fig. 4 shows a front end elevation partly broken away of the same mining machine.

Figs. 5, 6, and 7 are diagrams showing the mining machine of Fig. 1, arranged for executing the main cut, the starting cut, and the loading movement, respectively.

Referring to the drawings, and the embodiment of my invention there shown, I have there disclosed for the sake of illustrating one concrete form of my invention, a mining machine of the well-known cutter chain type provided with the cutter bar 1 projecting therefrom and adapted to under-cut the wall of the mine with a horizontal kerf as the machine is moved transversely in the direction of cutter bar length or in the direction of the arrow shown in Fig. 1.

The cutter bar, as usual, carries a suitable cutter chain 2 provided with the usual

cutters 3 and is driven from the driving sprocket wheel 4 (Fig. 3). The latter is mounted to be driven by means of the large beveled gear 5 which meshes with the beveled pinion 6, the latter secured to the armature shaft 7 of the electric driving motor, the frame of which is shown at 8.

While any suitable construction may be employed for traversing the machine while cutting, in the present instance supporting means are provided upon and with which the machine is adapted to move along the mine, and preferably, as in the machine of the prior patent to Mitchell No. 656,414, such means is provided in the form of a bottom member or shoe 9 upon which the machine is adapted to slide and, if desired, directly upon the bottom or floor of the mine.

In order to hold the cutter chain and the cutter bar in the desired relation against the work as the machine is fed along, guiding means are provided, the same consisting of one or more ropes, cables or other flexible guiding members kept under tension and so associated with the machine that the cutter bar, as it travels, is held up to the work without the necessary use of rails or other like guiding supports.

In the illustrated form of my invention I provide for this purpose flexible guiding means, herein in the form of a wire rope or cable presenting two end portions or lengths 10 and 11, both connected to a fixed support, one on the advancing side of the machine and the other on the receding side thereof, and one connected to the machine relatively adjacent its wall or cutting end and the other relatively near the opposite end thereof. The machine may be fed along the flexible guiding means in any suitable manner, either by hand or by motive power. In case hand power is employed for this purpose, it may be applied to progress the machine in any suitable manner, as by prying it along the mine bottom, while the flexible guiding means effectively serve to guide the machine and keep the cutters up to the work. In this case, the flexible guiding means performs merely a guiding function; while on the other hand, if some means be employed to engage the flexible guiding means and propel the machine with such engagement therewith, the guiding means

will serve also as a cooperating part of the driving means.

These two lengths or portions are presented by a single unbroken length of cable, 5 a single winding drum 12 being employed with a grooved surface to secure a better grip upon the cable. The leading cable portion 10 is coiled for a sufficient number of turns to insure the necessary frictional grip, 10 and thence passes to the opposite side of the machine, where it presents the receding portion or length 11.

In the present machine (see Fig. 5) the cable 10 in making the main or lateral cut 15 extends directly from the drum 12 to an anchor 13, or other fixed support at the end of the coal face to which the end of the cable has a fixed connection. The anchor 13 may be of any suitable construction, such as that 20 shown in the aforesaid Mitchell patent.

The cable 11, in passing from the machine, leads from the drum over and about a suitably positioned guiding sheave 14, thence back to the rear or opposite end of the machine, over and about the guiding sheaves 15 25 and 16, and thence to a fixed support 17 (see Fig. 5) at the receding side of the machine, to which support its free end is fastened. Preferably there is provided means for taking in or letting out the trailing cable 11 30 upon the machine itself. For this purpose the two guiding sheaves 15 and 16 are together mounted upon a movable carrier, such as the swinging arm 18 herein mounted on a 35 vertical axis on the rear end of the machine, the position of which may be adjusted by means of the ratchet wheel 19, to which the arm is fixedly secured. For this purpose there is provided the pivoted ratchet lever 40 20, pawl 21 and locking dog 22 by means of which the ratchet wheel and arm, together with the attached guiding sheaves, may be adjusted to different positions. As the arm is swung lefthandedly, as viewed in Fig. 1, 45 the trailing cable is let out more or less, while when it is swung righthandedly, as viewed in the same figure, the cable will obviously be drawn in more or less. In order to take up or let out the cable 11 by means apart 50 from the machine, the fixed support 17 may, if desired, be in the form of an adjustable take-up jack, having for example a construction similar to that of the take-up jack shown in Figs. 16 and 17 of the aforesaid 55 Mitchell patent, although this form obviously does not possess the advantages of the form previously described.

It will be seen that the cable portion 10, when placed under tension, is so connected to 60 the machine as to exert its draught upon the same adjacent the wall end thereof, while the resultant draught of the trailing cable 11 is nearer the opposite end thereof. With the two cable portions, therefore, placed under 65 tension and with the cutter chain in position

against the work they serve to hold the cutter bar against the work as the machine travels along and in a position which can be regulated by taking in or letting out the trailing cable 11 to swing the machine more or less 70 about its connection to the advancing cable 10 as a fulcrum.

Referring now to the mechanism for the winding drum 12, the latter is driven from the driving motor 8 through suitable speed reduction gearing, which permits the employment of either one of two speeds the direction of rotation of the drum being herein reversed when the change of speed is effected. The drum is mounted to turn upon bearings 75 25 presented by the head portion 26 of the machine and is arranged coaxially with the motor, so that its main shaft 27 extends rearwardly through the hollow motor shaft 7 to the speed change mechanism at the rear of 80 the motor. To turn the drum driving shaft 27, the latter is provided with any suitable form of change clutching device, a well-known form of which is herein shown in Fig. 3 as applied to the shaft. Herein this 85 consists of the grooved clutch member 28 fixedly secured to the shaft to rotate therewith, but slidable thereon, carrying gripping members 29 and 30 connected to the said clutch member by the toggle links 31 90 and 32, respectively, so that when moved in one direction or the other the clutch member may be gripped either to the clutch casing 33 or 34 according to the direction in which the said clutch member is moved. The clutch 95 member may be moved at will in either direction by means of the clutch lever 35 leading to the short upright shaft 36 carrying at its end the eccentric or cam 37 seated in the groove of the clutch member 28.

The clutch casing 33 is fixedly secured to the hollow motor shaft 7 so as to be constantly driven thereby so that, when engaged therewith, the clutch member and the drum driving shaft are driven at a high rate of 100 speed directly from the motor.

On the other hand, the clutch casing 34 is connected to the beveled gear 38 meshing with the beveled pinion 39, the latter secured to the upright driving shaft 40 constantly driven by the large beveled gear 5. When the clutch member 28, therefore, is engaged with the clutch casing 34, the drum driving shaft 27 is driven in the opposite direction and at a reduced rate of speed 115 through the armature shaft 7, beveled gear 5, the upright shaft 40, the beveled gears 39 120 and 38, and clutch casing 34.

To secure further reduction to the movement of the winding drum additional speed 125 reduction gearing is employed, preferably of the planetary type, and herein located within the walls of the drum. Referring to Figs. 2 and 4 the drum driving shaft at its forward end has keyed thereto the small 130

driving pinion 41 meshing with an intermediate pinion 42, the latter journaled upon a stud 43 fixed in the arm 44 which is free to turn about the shaft 27. The gear 42, however, engages with an internal gear 45 cut on the inner wall of the drum 12 so that the arm 44 has a resultant slow turning movement which is communicated to the small pinion 46 fixed to the arm and turning coaxially therewith.

10 A second reduction is secured by providing the second intermediate gear 47 meshing with the pinion 46 and also with the internal gear 45, the latter carried by the arm 48 also turning about the shaft 27. Movement is communicated to the drum from the arm 48 by means of the small pinion 49 fixed to the arm, which pinion meshes with the intermediate gear 50 turning upon a fixed journal 20 on the head 26 and meshing with the internal gear 45 on the drum. By means of this speed reduction gearing the high speed driving movement of the motor in one direction is transformed into a slow drum turning movement in the same direction.

Referring to Fig. 5 the operation of the machine in effecting the lateral or main cut will be clear. With the cables arranged as therein shown and as previously described, 30 the clutch lever 35 may be turned to impart to the winding drum the slow speed turning movement so that the cable 10 is slowly wound in at the same rate as the cable 11 is payed out. This results in maintaining the initially established tension on the cable 11 so that the machine in its travel is held in and against the work. The cutters (which move in the direction of the arrow shown in Fig. 1) act to draw the machine in, and the trailing cable tends to swing the cutter bar forward about the fulcruming attachment of the cable 10 to the machine, holding the cutters against the coal.

40 By reference to Fig. 5 it will be seen that the machine is held in the cut by the opposing pull of the two cables exerted one near the wall and the other more remote therefrom. By adjustably taking up or letting out the receding cable 11, therefore, the angular inclination of the machine may be adjusted. Such adjustment in the illustrated machine may be effected either at the machine by the manipulation of the ratchet and pawl mechanism described, or away from the machine by the manipulation of the take-up jack 17. It will be seen that the two cable portions constitute a stationary guiding member on which the machine travels as it cuts.

60 Figure 6 shows an arrangement of cables which may be employed in making this starting or sumping cut. Under such condition the advancing cable 10 leads from the winding drum 12 about an appropriately positioned and removably mounted guide sheave

51, thence forward to a fixed support 52 located near the face of the coal. When the clutch lever is turned to give the slow speed the winding drum will be turned slowly in such a direction as to wind in the cable 10, 70 drawing the cutter bar and cutters into the coal.

In Fig. 7 I have shown the arrangement of cables for loading the machine upon the truck or upon a starting frame, such for example as the frame 53, which is customarily employed to guide the machine in making the starting or sumping cut. For this purpose the trailing cable 11 is carried back about the guiding sheaves 15 and 16, and 75 thence directly back to an attachment 54 at the back of the starting frame or truck as the case may be. To better align the cable for this movement the sheave 16 is transferred from a position at the end of 80 the swinging arm 18 to a position directly over the axis of the arm. With the cable thus arranged the clutch lever is turned to give a quick winding movement to the drum, thus acting to turn the winding drum re- 85 versely at a high rate of speed winding in the cable 11 and drawing the machine upon a starting frame at a more rapid rate of travel than is employed in the cutting movement. During this operation the free end 90 of the cable may be taken up by the attendant, and the movement of the machine may be controlled by the take-up. Other arrangements of cables may be utilized to cause the machine to feed itself from one position to 100 another about the mine bottom, as will be obvious to those skilled in the art.

Preferably I provide a hood or casing 55 encircling the winding drum 12, or the greater portion of the periphery thereof, and 105 lying closely adjacent the cable coils, so that a uniform helical relation of the latter will be enforced whether or not tension of the cables is preserved. This opposes any tendency of the coils to open and climb one over the next adjacent one, or otherwise to become entangled.

In machines of the type described, irregularities in the face of the coal beneath which the cutter bar projects, are apt to deflect the machine more or less out of a straight path, with the result of producing a kerf of varying depth. Preferably I employ upon a machine of this type means for cutting off the overhanging or projecting coal apt to obstruct the passage of the machine as it feeds along the face. To this end (see Figs. 1 and 3) the drum turning shaft 27 is extended through the head 26 and has fixedly secured at its end the revolving cutter head 57 provided with one or more sets of cutters 58 so positioned that they act to trim off the coal in advance of the machine so that the coal directly in front of the machine presents a plane face.

Attention is also directed to the fact that, as in the case of my co-pending application, Ren. Ser. No. 361,110, of which this case is a division, as a result of my improved construction and arrangement of the feed operating member or drum, the take-up member, the cutting mechanism, and the driving mechanism for the several elements, including the horizontal motor and the cutter chain driving sprocket whose axis is longitudinally spaced from the motor herein in rear of the same, an exceedingly low construction is provided well adapted to work in low coal, at the same time that due to the possibility of driving the mechanism from the rear end of the motor, a structure is provided which not only has this and other advantages but in common with the structure of my co-pending case is also well adapted for use under bad roof conditions. It will also be noted that herein, as distinguished from the construction shown in my co-pending application, through the single stationary strands extending in opposite directions from the opposite ends of the frame, the amount of flexible connection necessary to be handled and the consequent delays are maintained at a minimum at the same time that it is made possible to eliminate all moving strands, while through the provision of my improved flexible feeding means and my improved cooperating feed controlling means operating on the slack side of the flexible connections, it is possible to provide simplified mechanism adapted to propel the machine readily as desired and to control the same from the machine whenever desired over a wide range without delay and with a minimum of effort.

While I have herein shown for the purpose of illustration one specific form of my invention, it is to be understood that the same is not limited to the details of construction, or the relative arrangement of parts, or the application herein made of the invention, or the particular form of mining machine shown, but that extensive deviations may be made in respect to these features from the showing made without departing from the spirit of the invention.

50 Claims:

1. In a mining machine, an elongated machine frame slidable relative to a mine bottom, cutter mechanism extending longitudinally thereof from one end thereof, flexible guiding means having its free ends extending laterally from the front and rear ends of said frame and fixed to points in the mine at the advancing and receding sides of said frame, mechanism on said frame for propelling the latter relative to said guiding means, and a movable frame angling take-up on said frame around which a slack portion of said flexible means passes at a point between its fixed point and said propelling mechanism.

2. In a mining machine, an elongated machine frame slidable relative to a mine bottom, cutting mechanism extending longitudinally thereof from one end thereof, flexible guiding means having its free ends extending laterally from the front and rear ends of said frame and fixed to points in the mine at the advancing and receding sides of said frame, mechanism on said frame for propelling the latter relative to said guiding means, and a movable frame angling take-up on said frame around which the rearwardly located laterally extending portion of said flexible means passes at a point between its fixed point and said propelling mechanism. 70

3. In a mining machine, an elongated machine frame slidable relative to a mine bottom, cutting mechanism extending longitudinally thereof from one end thereof, flexible guiding means having its free ends extending laterally from the front and rear ends of said frame and fixed to points in the mine at the advancing and receding sides of said frame, mechanism on said frame for propelling the latter relative to said guiding means, a movable frame angling take-up on said frame around which passes the portion of said flexible means on the receding side of said frame, and means whereby said take-up may be adjusted in either direction. 75

4. In a mining machine, an elongated machine frame slidable relative to a mine bottom, cutting mechanism extending longitudinally thereof from one end thereof, flexible guiding means having its free ends extending laterally from the front and rear ends of said frame and fixed to points in the mine at the advancing and receding sides of said frame, mechanism on said frame for propelling the latter relative to said guiding means, a movable frame angling take-up on said frame around which passes the portion of said flexible means on the receding side of said frame, and means for holding said tape-up in different positions of adjustment. 80

5. In a mining machine, an elongated machine frame slidable relative to a mine bottom, cutting mechanism extending longitudinally thereof from one end thereof, flexible feeding mechanism including flexible feeding portions disposed laterally in front and rear of said frame from opposite ends thereof and a single power driven rotatable member paying out one of said portions as it draws in the other, and an independently movable frame angling take-up on said frame movable to vary the effect of said paid out portion. 85

6. In a mining machine, an elongated machine frame slidable relative to a mine bottom, cutting mechanism extending longitudinally thereof from one end thereof, flexible feeding mechanism including flexible feed- 90

- ing portions disposed laterally in front and rear of said frame from opposite ends thereof and a single power driven rotatable member paying out one of said portions as it draws in the other, an independently movable frame angling take-up on said frame movable to vary the effect of said paid out portion, and means for moving said take-up.
7. In a mining machine, an elongated machine frame, slidable relative to a mine bottom, cutting mechanism extending longitudinally thereof from one end thereof, flexible feeding mechanism including flexible feeding portions disposed laterally in front 10 and rear of said frame from opposite ends thereof and a single power driven rotatable member paying out one of said portions as it draws in the other, an independently movable frame angling take-up on said frame movable to vary the effect of said paid out portion, and means whereby said take-up may be adjusted in opposite directions.
8. In a mining machine, an elongated machine frame slidable relative to a mine bottom, cutting mechanism extending longitudinally thereof from one end thereof, flexible feeding mechanism including flexible feeding portions disposed laterally in front 15 and rear of said frame from opposite ends thereof and a single power driven rotatable member paying out one of said portions as it draws in the other, an independently movable frame angling take-up on said frame movable to vary the effect of said paid out portion, and means for holding said take-up in different positions of adjustment.
9. In a mining machine, an elongated machine frame slidable relative to a mine bottom, cutting mechanism extending longitudinally thereof from one end thereof, flexible feeding mechanism including flexible feeding portions extending laterally from the opposite ends of said frame in single 20 strands to fixed points on the advancing and receding sides of said frame and a single power driven feed operating member paying out one of said portions as it draws in the other, and a movable frame angling take-up on said frame movable to vary the effect of said paid out portion.
10. In a mining machine, an elongated machine frame slidable relative to a mine bottom, cutting mechanism extending longitudinally thereof from one end thereof, flexible feeding mechanism including flexible feeding portions extending laterally from the opposite ends of said frame in single 25 strands to fixed points on the advancing and receding sides of said frame and a single power driven feed operating member paying out one of said portions as it draws in the other, and a movable frame angling take-up on said frame movable to vary the effect of said paid out portion.
11. In a mining machine, an elongated machine frame slidable relative to a mine bottom, cutting mechanism extending longitudinally thereof from one end thereof, flexible feeding mechanism including a single length of flexible feeding member having portions extending laterally from the opposite ends of said frame in single strands to fixed points on the advancing and receding sides of said frame and a single power driven feed operating means paying out one of said portions as it draws in the other, and an adjustable cooperating frame angling take-up on said frame movable to vary the effect of said receding portion.
12. In a mining machine, an elongated machine frame slidable relative to a mine bottom, cutting mechanism extending longitudinally thereof from one end thereof, flexible feeding mechanism including flexible feeding portions extending laterally from the opposite ends of said frame in single strands to fixed points on the advancing and receding sides of said frame and a single power driven feed operating member paying out one of said portions as it draws in the other, and a cooperating frame angling take-up on said frame operable at will independently of said feed operating member and movable to vary the effect of said paid out portion.
13. In a mining machine, an elongated machine frame slidable relative to a mine bottom, cutting mechanism extending longitudinally thereof from one end thereof, flexible feeding mechanism including a single length of flexible feeding member having portions extending laterally in single strands from the opposite ends of said frame to fixed points on the advancing and receding sides of said frame and power driven feed operating means paying out one of said portions as it draws in the other, and a cooperating frame angling take-up on said frame around which the paid out portion passes at a point on the receding side of said feed operating member, and movable at will independently of said feed operating member to vary the effect of said receding portion.
14. In a mining machine, a machine frame slidable on its bottom relative to a mine bottom, a horizontally disposed motor thereon extending longitudinally thereof, cutting mechanism projecting from one end of said frame and driven by said motor, flexible feeding mechanism including flexible feeding portions disposed laterally in opposite directions from opposite ends of said frame and feed operating means disposed on said frame and including a member driven from the rear end of said motor and operative to wind in the flexible feeding portion on the advancing side of said frame, and means on

said frame for varying the angle of said frame to a face operating on the flexible feeding portion on the receding side of said frame to vary the effect thereof.

5 15. In a mining machine, a machine frame 70
slidable on its bottom relative to a mine bottom, a horizontally disposed motor thereon extending longitudinally thereof, cutting mechanism projecting from one end of said frame and driven by said motor, flexible feeding mechanism including flexible feeding portions disposed laterally in opposite directions from opposite ends of said frame and feed operating means disposed on said

10 frame and including a member driven from the rear end of said motor and operative to wind in the flexible feeding portion on the advancing side of said frame, and means on

15 said frame for varying the angle of said frame to a face operating on the flexible feeding portion on the receding side of said frame to 75

20 increase or decrease the effective length thereof.

16. In a mining machine, a machine frame 80
25 slidable on its bottom relative to a mine bottom, a horizontally disposed motor thereon extending longitudinally thereof, cutting mechanism projecting from one end of said frame and driven by said motor, flexible feeding mechanism including flexible feeding portions disposed laterally in opposite directions from opposite ends of said frame and feed operating means disposed on said

30 frame and driven from the rear end of said motor and operative to wind in either of

35 said flexible feeding portions at will, and means on said frame for varying the angle of said frame to a face operating on the flexible feeding portion on the receding side 85

40 of said frame to vary the effect thereof.

17. In a mining machine, a machine frame 90
50 slidable on its bottom relative to a mine bottom, a horizontally disposed motor thereon extending longitudinally thereof, cutting mechanism projecting from one end of said frame and driven by said motor, flexible feeding and guiding mechanism including flexible feeding portions disposed laterally in opposite directions from opposite ends of

55 said frame and feed operating means disposed on said frame and driven from the rear end of said motor operative to wind in one of said flexible feeding portions and unwind the other, and means on said frame 95

60 for varying the angle of said frame to a face operating on the flexible feeding portion on the receding side of said frame to 100

65 vary the effect thereof.

18. In a mining machine, a machine frame 105
70 slidable on its bottom relative to a mine bottom, a horizontally disposed motor thereon extending longitudinally thereof, cutting mechanism projecting from one end of said frame and driven by said motor, flexible feeding mechanism including flexi-

ble feeding portions disposed laterally in opposite directions from opposite ends of said frame and feed operating means disposed on said frame and driven from the rear end of said motor operative to shorten 70
or lengthen either of said flexible feeding portions at will, and means on said frame for varying the angle of said frame to a face operating on the flexible feeding portion on the receding side of said frame to 75
vary the effect thereof.

19. In a mining machine, a machine frame 80
slidable on its bottom relative to a mine bottom, a horizontally disposed motor thereon extending longitudinally thereof, cutting mechanism on said frame including a cutter chain sprocket in rear of said motor, and driven thereby, flexible feeding mechanism for feeding said frame laterally to undercut a face comprising flexible 85
feeding portions disposed laterally in advance of and to the receding side of said frame from opposite ends thereof, and feed operating and controlling means for shortening said advance flexible portion and lengthening said receding flexible portion during machine movement including a feed operating member driven by said motor and a cooperating frame angling take-up carried on said frame. 90

20. In a mining machine, a machine frame 95
slidable on its bottom relative to a mine bottom, a horizontally disposed motor thereon extending longitudinally thereof, cutting mechanism on said frame including 100
a cutter chain sprocket in rear of said motor and driven thereby, flexible feeding mechanism for feeding said frame laterally to undercut a face comprising stationary single strand flexible feeding portions dis- 105
posed laterally in advance of and to the receding side of said frame from opposite ends thereof, and feed operating and controlling means for shortening said advance flexible portion and lengthening said receding flexible portion during machine movement including a feed operating member driven by said motor and a cooperating frame angling take-up carried on said frame. 110

21. In a mining machine, a machine frame 115
slidable on its bottom relative to a mine bottom, a horizontally disposed motor thereon extending longitudinally thereof, cutting mechanism on said frame 120
including a cutter chain sprocket in rear of and driven from the rear end of said motor, flexible feeding mechanism for feeding said frame laterally to undercut a face comprising flexible feeding portions dis- 125
posed laterally in advance of and to the receding side of said frame from opposite ends thereof, and feed operating means for shortening said advance flexible portion and lengthening said receding flexible por- 130

tion during machine movement including a feed operating member driven from the rear end of said motor and a cooperating frame angling take-up carried on said 5 frame.

22. In a mining machine, a machine frame 10 slidable on its bottom relative to a mine bottom, a horizontally disposed motor thereon extending longitudinally thereof, cutting mechanism on said frame including a cutter chain sprocket which is rotatable on an axis disposed in rear of and is also driven from the rear end of said motor, flexible feeding mechanism for feeding said 15 frame laterally to undercut a face comprising stationary single strand flexible feeding portions disposed laterally in advance of and to the receding side of said frame from opposite ends thereof, and feed operating means for shortening said advance 20 flexible portion and lengthening said receding flexible portion during machine movement including a feed operating member rotatable on a horizontal axis and driven 25 from the rear end of said motor and a cooperating frame angling take-up carried on said frame, the driving connections for said feed operating member including elements 30 disposed in rear of said motor and above the bottom thereof.

23. In a mining machine, a machine frame slidable on its bottom on a mine bottom, a horizontal motor disposed longitudinally of said frame, cutter mechanism on 35 said frame and driven from said motor, flexible feeding means for feeding said frame laterally to undercut a coal face comprising flexible feeding portions disposed laterally in advance of said frame and on 40 the receding side thereof from opposite ends thereof, feed operating means rotatable on a single axis and operated by power from the rear end of said motor to shorten one of said portions and lengthen the other, 45 and manually controlled frame angling means on said frame operable to vary the effect of said lengthened portion.

24. In a mining machine, a machine frame slidable on its bottom on a mine bottom, 50 horizontal motor disposed longitudinally of said frame, cutter mechanism on said frame and driven from said motor, flexible feeding means for feeding said frame laterally to undercut a coal face comprising flexible 55 feeding portions disposed laterally in advance of said frame and on the receding side thereof and from opposite ends thereof, feed operating means rotatable relative to a horizontal axis and operated by power from the rear end of said motor to shorten one of said portions and lengthen the other, and manually controlled frame angling means 60 on said frame operable to vary the effect of said lengthened portion.

25. In a mining machine, a machine frame

slidable on its bottom on a mine bottom, a horizontal motor disposed longitudinally of said frame, cutter mechanism on said frame and driven from said motor, flexible feeding means for feeding said frame laterally to 70 undercut a coal face comprising stationary single strand flexible feeding portions disposed in advance of said frame and on the receding side thereof and from opposite ends thereof, feed operating means rotatable on a single axis and operated by power from the rear end of said motor operative to shorten one of said portions and lengthen the other, and manually controlled frame angling means on said frame operable to vary 75 the effect of said lengthened portion.

26. In a mining machine, a machine frame slidable on its bottom on a mine bottom, a horizontal motor disposed longitudinally of said frame, cutter mechanism on said frame and driven from said motor, flexible feeding means for feeding said frame laterally to undercut a coal face comprising stationary single strand flexible feeding portions disposed in advance of said frame and on the receding side thereof and from opposite ends thereof, feed operating means rotatable relative to a horizontal axis and operated by power from the rear end of said motor operative to shorten one of said portions and 80 lengthen the other, and manually controlled frame angling means on said frame operable to vary 85 the effect of said lengthened portion.

27. In a mining machine, a machine frame slidable on its bottom on a mine bottom, cutting mechanism at one end thereof, flexible feeding mechanism for feeding said frame laterally to undercut a coal face including feeding means disposed on a horizontal axis and a plurality of cooperating flexible feeding portions operatively connected between said frame and points in the mine and disposed laterally one in advance of said frame from the front end thereof and the other to the receding side of said frame from the rear end thereof, a horizontally disposed motor extending longitudinally of said frame and driving said cutting mechanism, and driving connections between the rear end of said motor and said feeding means selectively operable to wind in either of said portions.

28. In a mining machine, a machine frame slidable on its bottom on a mine bottom, cutting mechanism at one end thereof, flexible feeding mechanism for feeding said frame laterally to undercut a coal face including feeding means disposed on a horizontal axis and a plurality of cooperating flexible feeding portions operatively connected between said frame and points in the mine and disposed one in advance of said frame from the front end thereof and the other on the receding side of said frame from the rear end thereof, a horizontally 115 120 125 130

disposed motor extending longitudinally of said frame driving said cutting mechanism, and driving connections between the rear end of said motor and said feeding means including a friction mechanism and selectively operable to wind in either of said portions.

29. In a mining machine, a machine frame 10
slidable on its bottom on a mine bottom, cutting mechanism at one end thereof, flexible feeding mechanism for feeding said frame laterally to undercut a coal face including feeding means disposed on a horizontal axis and a plurality of cooperating stationary single strand flexible feeding portions operatively connected between said frame and fixed points in the mine and disposed one in advance of said frame from the front end thereof and the other on the receding side of said frame from the rear end thereof, a horizontally disposed motor extending longitudinally of said frame driving said cutting mechanism, and driving connections between the rear end of said motor and 20
said feeding means selectively operable to wind in either of said portions.

30. In a mining machine, a machine frame 30
slidable on its bottom on a mine bottom, cutting mechanism at one end thereof, flexible feeding mechanism for feeding said frame laterally to undercut a coal face including feeding means disposed on a horizontal axis and a single length of flexible feeding member having a plurality of cooperating stationary single strand flexible feeding portions operatively connected between said frame and fixed points in the mine and disposed one in advance of said frame from the front end thereof and the 40
other on the receding side of said frame from the rear end thereof, a horizontally disposed motor extending longitudinally of said frame driving said cutting mechanism, and driving connections between the rear end of said motor and said feeding means selectively operable to wind in either of said portions.

31. In a mining machine, a machine frame 50
slidable on its bottom on a mine bottom, cutting mechanism at one end thereof including a cutter chain driving sprocket, flexible feeding mechanism for feeding said frame laterally to undercut a coal face including feeding means and a plurality of cooperating flexible feeding portions operatively connected between said frame and points in the mine and disposed one in advance of said frame from the front end thereof and the other on the receding side of said frame from the rear 60
end thereof, a horizontally disposed motor on said frame in front of said sprocket and having one of its ends operatively connected thereto, driving connections between the same end of said motor and said feeding means and selectively operable to wind in either 65
of said portions.

either of said portions, and means on said frame for varying the effect of said receding portion.

32. In a mining machine, a machine frame 70
slidable on its bottom on a mine bottom, cutting mechanism at one end thereof including a cutter chain driving sprocket, flexible feeding mechanism for feeding said frame laterally to undercut a coal face including feeding means and a plurality of cooperating 75
stationary single strand flexible feeding portions operatively connected to fixed points in the mine and disposed one in advance of said frame from the front end thereof and the other on the receding side of said frame 80
from the rear end thereof, a horizontally disposed motor on said frame in front of said sprocket and having one of its ends operatively connected thereto, driving connections between the same end of said motor 85
and said feeding means selectively operable to wind in either of said portions, and means on said frame for varying the effect of said receding portion.

33. In a mining machine, a machine frame 90
slidable on its bottom on a mine bottom, cutting mechanism at one end thereof including a cutter chain driving sprocket, flexible feeding mechanism for feeding said frame laterally to undercut a coal face including feeding means and a plurality of cooperating 95
stationary single strand flexible feeding portions operatively connected to fixed points in the mine and disposed one in advance of said frame from the front end thereof and the other on the receding side of said frame from the rear end thereof, a horizontally disposed motor extending longitudinally of said frame 100
in front of said sprocket and driving said sprocket from its rear end, driving connections between the rear end of said motor and said feeding means selectively operable to wind in either of said portions, and means on said frame for varying the effect of said 105
receding portion.

34. In a mining machine, a machine frame 110
slidable on its bottom on a mine bottom, cutting mechanism at one end thereof including a cutter chain sprocket, flexible feeding mechanism for feeding said frame laterally to undercut a coal face including feeding means and a cooperating single length of flexible feeding member having a plurality 115
of stationary single strand flexible feeding portions operatively connected to fixed points in the mine and disposed one in advance of said frame from the front end thereof and the other on the receding side of said frame from the rear end thereof, a horizontally disposed motor extending longitudinally of said frame in front of said 120
sprocket and driving said sprocket from its rear end, driving connections between the rear end of said motor and said feeding means selectively operable to wind in either 125
of said portions.

of said portions, and means on said frame for varying the effect of said last mentioned portions.

35. In a mining machine, a machine frame 5 slidable on its bottom on a mine bottom, a motor thereon, cutting mechanism projecting from one end of said frame and driven by said motor, flexible feeding mechanism for propelling said frame laterally to form 10 a kerf in a face including a plurality of flexible feeding portions extending in advance of and at the receding side of said frame from the opposite ends thereof, and feed operating and controlling means includ- 15

15 including a feed operating member disposed in front of said motor and a rotatable take-up disposed on said frame in rear of said motor and on a vertical axis.

36. In a mining machine, a machine frame 20 slidable on its bottom on a mine bottom, a motor thereon, cutting mechanism projecting from one end of said frame and driven by said motor including a cutter driving member rotatable on a vertical axis disposed 25 in rear of said motor, flexible feeding mechanism for propelling said frame laterally to form a kerf in a face including a plurality of flexible feeding portions extending in advance of and at the receding side of said

30 frame from the opposite ends thereof, and feed operating and controlling means including a feed operating member disposed in front of said motor on a horizontal axis, a rotatable take-up disposed on said frame 35 in rear of said motor and on a vertical axis, and means whereby said take-up may be held in different positions.

37. In a mining machine, a machine frame slidable on its bottom on a mine bottom, a motor thereon, cutting mechanism projecting from one end of said frame and driven by said motor including a cutter driving member sprocket rotatable on a vertical axis disposed in rear of said motor, flexible feeding mechanism for propelling said frame laterally to undercut a face including a plurality of flexible feeding portions extending in advance of and at the receding side of said frame from the opposite ends thereof, 45 and feed operating means including a feed operating member disposed in front of said motor on a horizontal longitudinally disposed axis, a rotary take-up disposed on said frame in rear of said motor and on a vertical axis, and means whereby said take-up may be moved in opposite directions about its axis.

38. In a mining machine, a machine frame slidable on its bottom on a mine bottom, a motor thereon, cutting mechanism projecting from one end of said frame and driven by said motor including a cutter driving member rotatable on a vertical axis disposed in rear of said motor, flexible feeding mechanism for propelling said frame

laterally to undercut a face including a plurality of stationary single strand flexible feeding portions extending in advance of and at the receding side of said frame from the opposite ends thereof, feed operating means including a feed operating member disposed in front of said motor on a horizontal longitudinally disposed axis, and rotary take-up means disposed on said frame in rear of said motor and on a vertical axis.

39. In a mining machine, a machine frame slidable on its bottom on a mine bottom, a motor thereon, cutting mechanism projecting from one end of said frame and driven by said motor, flexible feeding mechanism for propelling said frame laterally to undercut a face including a single length of flexible feeding member having flexible feeding portions extending in advance of and at the receding side of said frame from the opposite ends thereof, feed operating means including a feed operating member disposed in front of said motor on a horizontal longitudinally disposed axis, and rotatable take-up means disposed on said frame in rear of said motor and on a vertical axis.

40. In a mining machine, a machine frame slidable on its bottom on a mine bottom, a motor thereon, cutter mechanism projecting from said frame and driven by said motor, a feed operating member longitudinally disposed on a horizontal axis in front of said motor and driven thereby, a take-up disposed in rear of said motor and on the rear end of said frame and movable about a vertical axis, and flexible feeding means including a single length of flexible feeding member having a plurality of stationary single strand flexible feeding portions disposable in advance of the frame and at the receding side of said frame from the opposite ends of said frame.

41. In a mining machine, a machine frame slidable on its bottom on a mine bottom, a motor thereon, cutter mechanism projecting from said frame and driven by said motor including a cutter driving member rotatable on a vertical axis disposed in rear of said motor, a feed operating member longitudinally disposed on a horizontal axis in front of said motor, a take-up disposed in rear of said motor and on the rear end of said frame and movable about a vertical axis, flexible feeding means including a plurality of stationary single strand flexible feeding portions disposable in advance and at the receding side of said frame from opposite ends of said frame and operable to direct said cutter mechanism laterally to undercut a face, and means whereby one of said flexible portions may be utilized to move said frame longitudinally.

42. In a mining machine, a machine

frame slidable on its bottom on a mine bottom, a motor thereon, cutter mechanism projecting from said frame and driven by said motor including a cutter driving sprocket rotatable on a vertical axis disposed in rear of said motor, a feed operating member longitudinally disposed on a horizontal axis in front of said motor, a take-up disposed in rear of said motor and on the rear 10 end of said frame and movable about a vertical axis, flexible feeding means including a plurality of stationary single strand flexible feeding portions disposable in advance and at the receding side of said frame and 15 operable to propel and guide said cutter mechanism laterally to undercut a face, and means whereby said flexible feeding portion disposable during lateral cutting on the receding side of said frame from said take-up 20 member may be utilized to move said frame longitudinally.

43. In a mining machine, a machine frame slidable on its bottom on a mine bottom, a motor thereon, cutting mechanism projecting from one end of said frame and 25 driven by said motor including a cutter driving member rotatable on a vertical axis disposed in rear of said motor, a feed operating member disposed in front of said 30 motor and driven thereby, a movable take-up disposed on said frame in rear of said motor and operable independently of said feed operating member, and flexible feeding mechanism for feeding said frame laterally 35 including portions cooperating with said feed operating member and take-up and extending laterally in opposite directions from the opposite ends of said frame in stationary single strand connections to fixed 40 points in advance of and at the receding side of the said frame.

44. In a mining machine, a machine frame slidable on its bottom on a mine bottom, a motor thereon, cutting mechanism projecting from one end of said frame and driven 45 by said motor, a feed operating member disposed in front of said motor and driven thereby, a movable take-up disposed on said frame in rear of said motor and operable 50 independently of said feed operating member, and flexible feeding mechanism including a single length of flexible feeding member 55 cooperating with said feed operating member and take-up and having portions extending laterally in opposite directions from opposite ends of said frame in stationary single strand connections to fixed points in advance of and at the receding side of said frame.

45. In a mining machine, a machine frame 60 slidable on its bottom on a mine bottom, a horizontal motor disposed longitudinally thereof, cutting mechanism driven by said motor including a cutter chain carrying bar 65 disposed longitudinally of said frame dur-

ing cutting and a cutter chain driving sprocket at one end of said motor, a feed operating member driven by said motor and disposed on said frame at the opposite end of said motor from said sprocket, a take-up 70 on said frame, and feeding and guiding means including a plurality of single strand stationary flexible feeding portions extending in front and rear of said frame from the opposite ends thereof and operable under the propulsion of said feed operating member and the control of said take-up to propel said bar laterally and along said forwardly directed portion at a cutting speed 75 to cut a kerf in a face.

46. In a mining machine, a machine frame 80 slidable on its bottom on a mine bottom, a horizontally disposed motor thereon extending longitudinally thereof, cutting mechanism including a cutter chain driving sprocket rotatable on a vertical axis disposed in rear of said motor, a feed operating member rotatable on a horizontal axis and disposed on the opposite end of said frame from 85 said sprocket, driving connections between the rear end of said motor and both said sprocket and said feed operating member, and a take-up carried on said frame movable independently of said feed operating member.

47. In a mining machine, a machine frame 90 slidable on its bottom on a mine bottom, a horizontally disposed longitudinally extending motor thereon, cutting mechanism projecting from one end of said frame including a cutter chain driving sprocket rotatable on a vertical axis disposed in rear of said motor, a feed operating member rotatable on a horizontal axis and disposed on the opposite end of said frame from 95 said sprocket, driving connections between the rear end of said motor and both said sprocket and said feed operating member, a take-up carried on said frame and movable independently of said feed operating member, and flexible feeding means controlled 100 by said feed operating member and take-up including a plurality of stationary single strand flexible feeding portions extending in opposite directions from opposite ends of 105 said frame.

48. In a mining machine, a machine frame 110 slidable on its bottom on a mine bottom, a cutter bar carried at one end of said frame and projecting longitudinally of said frame during cutting, a cutter chain rotatable about said bar, a horizontally disposed motor extending longitudinally of said frame, operative connections to one end of said motor for driving said cutter chain, a feed operating member driven by said motor and disposed on said frame at the opposite end of said motor from said chain driving connections, a take-up on said frame, and feeding and guiding means including a plurality 115 of single strand stationary flexible feeding portions extending in front and rear of said frame from the opposite ends thereof and operable under the propulsion of said feed operating member and the control of said take-up to propel said bar laterally and along said forwardly directed portion at a cutting speed 120 to cut a kerf in a face.

49. In a mining machine, a machine frame 125 slidable on its bottom on a mine bottom, a horizontal motor disposed longitudinally thereof, cutting mechanism driven by said motor including a cutter chain carrying bar disposed longitudinally of said frame dur-

of single strand stationary flexible feeding portions extending in front and rear of said frame from the opposite ends thereof and operable under the propulsion of said feed operating member and the control of said take-up to direct said bar at a cutting speed laterally relative to a face to cut a kerf therein.

5 mine bottom, a cutter bar carried at one end of said frame and projecting longitudinally of said frame during cutting, a cutter chain rotatable about said bar, a horizontally disposed longitudinally extending motor on said frame, operative connections to one end of said motor for driving said cutter chain, a feed operating member driven by

70

49. In a mining machine, an elongated machine frame slidable on its bottom on a mine bottom, a cutter bar carried at one end of said frame and projecting longitudinally of said frame during cutting, a cutter chain rotatable about said bar, a horizontally disposed motor extending longitudinally of said frame, operative connections to one end of said motor for driving said cutter chain, a feed operating member driven by said motor and disposed on said frame at the opposite end of said motor from said chain driving connections, a take-up on said frame, feeding and guiding means including a plurality of single strand stationary flexible feeding portions extending in front and rear of said frame from the opposite ends thereof and operable under the propulsion of said feed operating member and the control of said take-up to direct said bar at a cutting speed along said forwardly directed portion and laterally relative to a face to undercut the latter, and means for propelling said frame along said normally rearwardly directed portion at an increased speed when the free end of said portion is fixed at any point.

50. In a mining machine, an elongated machine frame, a cutter bar at one end thereof and projecting longitudinally of said frame during cutting, a cutter chain movable around said bar, a horizontally disposed motor on said frame including rotor means disposed longitudinally of said frame, operative connections between said motor and said cutter chain including a cutter chain driving sprocket at one end of said frame and driven from one end of said motor, a feed operating member driven by said motor and disposed at the opposite end of said frame and at the opposite end of said motor from said cutter chain driving sprocket.

50. In a mining machine, an elongated machine frame slidable on its bottom on a mine bottom, a cutter bar carried at one end of said frame and projecting longitudinally of said frame during cutting, a cutter chain rotatable about said bar, a horizontally disposed longitudinally extending motor on said frame, operative connections to one end of said motor for driving 105
40 said cutter chain, a feed operating member driven by said motor and disposed on said frame at the opposite end of said motor from said chain driving connections, a take-up on said frame, feeding and guiding 110
45 means including a plurality of single strand stationary flexible feeding portions extending in front and rear of said frame from the opposite ends thereof and operable under the propulsion of said feed operating member and the control of said take-up to direct 115
50 said bar at a cutting speed along said forwardly directed portion and laterally relative to a face to undercut the latter, and means for propelling said frame along said 120
55 normally rearwardly directed portion at an increased speed and under the control of said take-up when the free end of said portion is fixed at any point. 125
60

for front said cutter chain driving sprocket connections, and flexible feeding and guiding means operable upon rotation of said feed operating member to propel said bar laterally relative to a face at a cutting speed including a single stationary strand extending laterally from the front end of said frame to a fixed point in advance of said frame and a cooperating single stationary strand extending laterally from a point nearer the opposite end of said frame to a fixed point in rear of said frame. 130
53. In a mining machine, an elongated machine frame, a cutter bar at one end thereof and projecting longitudinally of said frame during cutting, a cutter chain movable around said bar, a horizontally disposed motor on said frame including rotor means disposed longitudinally of said frame, operative connections between said motor and said cutter chain including a cutter chain driving sprocket at one end of said frame and driven from one end of said motor, a feed operating member driven by said motor and disposed at the opposite end of said frame and at the opposite end of said motor from said cutter chain driving sprocket connections, and flexible feeding and guiding means operable upon rotation of said 135
65

51. In a mining machine, an elongated machine frame slidable on its bottom on a feed operating member to propel said bar laterally relative to a face at a cutting speed 130

including a single stationary strand extending laterally from the front end of said frame to a fixed point in advance of said frame and a cooperating single stationary strand extending laterally from a point nearer the opposite end of said frame to a fixed point in rear of said frame, and means for at will propelling said frame in an opposite direction and at an increased speed along said operating strand in different positions thereof.

54. In a mining machine, an elongated machine frame slidable on its bottom on a mine bottom, a cutter bar carried at one end of said frame, a cutter chain rotatable about said bar, a horizontally disposed motor extending longitudinally of said frame, operative connections for driving said cutter chain from said motor, a feed operating member disposed on a horizontal axis and driven from the rear end of said motor, a frame angling take-up on said frame, feeding and guiding means including a plurality of flexible feeding portions extending in front and rear of said frame from the opposite ends thereof and operable under the propulsion of said feed operating member and the control of said take-up to direct said bar at a cutting speed along said forwardly directed portion and laterally relative to a face to cut a kerf therein, and means for propelling said frame along said rearwardly directed portion at an increased speed and under the control of said take-up when said portion is connected in different relations.

55. In a mining machine, an elongated machine frame slidable on its bottom on a mine bottom, a cutter bar carried at one end of said frame and projecting longitudinally therefrom during cutting, a cutter chain rotatable about said bar, a horizontally disposed motor extending longitudinally of said frame, operative connections for driving said cutter chain from said motor, a feed operating member disposed on a horizontal axis and driven from the rear end of said motor, a frame angling take-up on said frame, feeding and guiding means including a plurality of single strand stationary feeding portions extending in front and rear of said frame from the opposite ends thereof and operable under the propulsion of said feed operating member and the control of said take-up to direct said bar at a cutting speed along said forwardly directed portion and laterally relative to a face to cut a kerf therein, and means for propelling said frame along said rearwardly directed portion at an increased speed when the free end of said rearwardly directed portion is fixed at any point.

56. In a mining machine, an elongated machine frame slidable on its bottom on a mine bottom, a cutter bar carried at one end

of said frame, a cutter chain rotatable about said bar, a horizontally disposed motor extending longitudinally of said frame, operative connections for driving said cutter chain from said motor, a feed operating member disposed on a horizontal axis and driven from the rear end of said motor, a frame angling take-up on said frame, feeding and guiding means including a plurality of flexible feeding portions extending in front and rear of said frame from the opposite ends thereof and operable under the propulsion of said feed operating member and the control of said take-up to direct said bar at a cutting speed along said forwardly directed portion and laterally relative to a face to cut a kerf therein, and means for propelling said frame along said rearwardly directed portion at an increased speed and under the control of said take-up when said portion is connected in different relations.

57. In a mining machine, an elongated machine frame slidable on its bottom on a mine bottom, a cutter bar carried at one end of said frame and projecting longitudinally therefrom during cutting, a cutter chain rotatable about said bar, a horizontally disposed motor extending longitudinally of said frame, operative connections for driving said cutter chain from said motor, a feed operating member disposed on a horizontal axis and driven from the rear end of said motor, a frame angling take-up on said frame, feeding and guiding means including a plurality of single strand stationary feeding portions extending in front and rear of said frame from the opposite ends thereof and operable under the propulsion of said feed operating member and the control of said take-up to direct said bar at a cutting speed along said forwardly directed portion and laterally relative to a face to cut a kerf therein, and means for propelling said frame along said rearwardly directed portion at an increased speed and under the control of said take-up when the free end of said portion is fixed at any point.

58. In a mining machine, an elongated machine frame slidable on its bottom on a mine bottom, a cutter bar at one end thereof, a cutter chain movable around said bar, a horizontally disposed motor on said frame including rotor means disposed longitudinally of said frame, operative connections between said motor and said cutter chain including a cutter chain driving sprocket at one end of said frame and at one end of said motor and between said end of said frame and the adjacent end of said motor, and means for propelling said bar relative to a face at a cutting speed including a feed operating member driven by said motor and disposed at the opposite end of

- said frame and at the opposite end of said motor from said cutter chain driving sprocket and rotatable on an axis lying in a vertical plane which includes the longitudinal center line of said frame, a single strand stationary flexible feeding member cooperating with said feed operating member and extending in a direction parallel to the longitudinal center line of said frame 5 to a fixed point in advance of said frame and a guiding member adjacent said feed operating member and one edge of said frame for maintaining the adjacent end of said flexible member at a given distance from 10 the longitudinal center line of the machine as said feed operating member is rotated.
59. In a mining machine, a frame having a shoe upon which the same is movable over the mine bottom, cutting mechanism including a forwardly projecting rigid cutter bar and a cutter chain movable around the same, flexible feeding mechanism operatively connected at points on the advancing and receding sides of the frame and leaving 15 the frame at the opposite ends thereof, means on said frame for controlling the angle of said frame including a plurality of guiding members, and means for simultaneously adjusting said guiding members relative to 20 the frame.
60. In a mining machine, a frame having a shoe upon which the same is movable over the mine bottom, cutting mechanism including a forwardly projecting rigid cutter bar and a cutter chain movable around the same, flexible feeding mechanism operatively connected at points on the advancing and receding sides of the frame and leaving the frame at the opposite ends thereof, means 25 on said frame for controlling the angle of said frame including a pivoted frame having a plurality of sheaves mounted on vertical axes at its opposite ends, and means for swinging said frame about its pivot.
61. In a mining machine, a frame having a shoe upon which the same is movable over the mine bottom, cutting mechanism including a forwardly projecting rigid cutter bar and a cutter chain movable around the same, flexible feeding mechanism operatively connected at points on the advancing and receding sides of the frame and leaving the frame at the opposite ends thereof, means 30 on said frame for controlling the angle of said frame including a pivoted frame having a plurality of sheaves mounted on vertical axes at its opposite ends, and means for swinging said frame about its pivot.
62. In a mining machine, cutting mechanism, a support therefor slidable along the mine bottom, flexible guiding means connected to fixed supports on the advancing and receding sides of the machine, said guiding means leaving the machine at two 35 points, one near the wall or cutting end and the other nearer the opposite end thereof, a rotatable member on which said guiding means is wound, and means including a multiple friction clutch mechanism for 40 driving said member in opposite directions.
63. In a mining machine, a support, kerf cutting mechanism thereon, mechanism for feeding the support along the mine bottom, and face smoothing mechanism including a 45 rotatable cutter operatively connected to one of said mechanisms.
64. In a mining machine, the combination with cutting means of a support on which the machine is adapted to slide along the mine 50 bottom, flexible guiding means comprising an unbroken cable length connected to the machine, and connected also to fixed supports at opposite sides of the machine, said guiding means leaving the machine at two 55 points, one near the wall or cutting end and the other nearer the opposite end thereof, means for directing the course of the guiding means on the machine, including a pair of guiding sheaves and means for adjusting 60 the position of said sheaves to change the angular relation of the cutting means to the work.
- In testimony whereof, I have signed my name to this specification, in the presence 65 of two subscribing witnesses.
